WALTER L. MACK, OF TOLEDO, OHIO, ASSIGNOR, BY MESNE ASSIGNMENTS, TO AIR-WAY ELECTRIC APPLIANCE CORPORATION, OF TOLEDO, OHIO, A CORPORATION OF DELAWARE

APPARATUS FOR HEATING ROOMS

Application filed October 16, 1929, Serial No. 400,018. Renewed October 28, 1931.

This invention relates to heating, especially the heating of the rooms of houses, apartments, offices, stores, and so forth. It is one of the objects of the invention to accomplish 5 the heating of such places by directing the heating effort primarily to that portion of a room which is most in need of being heated, that is, the lower portion of a room. It is a further object of the invention to distribute 10 the heat over the whole or a substantial part of the lower portion of the room and at the same time to do so in such a manner that there will be no marked drafts of either hot or cold air or any rapid movement of the air 15 of a disagreeable or even of a noticeable character. It is also an object of the invention to distribute the heat positively and definitely as distinguished from the usual dependence upon the uncertain results of heat distribution from radiation and natural convection currents alone.

A further object of the invention is the production of suitable apparatus for carrying out the foregoing objects which shall be simple and compact in construction, clean and effective in operation, and which will not readily get out of order, in one form, the invention being sufficiently compact so that it is possible to install it between the adjacent 20 studs of an ordinary wall and between the floor and first cross bridging. A still further object of the invention is to obtain separate and effective control of the heating of each room so that when the apparatus is put into 25 operation the full heating effect may be obtained practically instantaneously and the operation of the apparatus for each particular room may be in accordance with the needs of that room.

In order to more clearly explain the invention, reference is made to the following description, taken in connection with the accompanying drawings showing certain structural features of the invention, and in which

Fig. 1 is a perspective view of a heating device shown in position between adjacent studs in the wall of a room;

Fig. 2 is a front elevation of the heater of Fig. 1 with the enclosing panel removed to show the interior of the heating device;

Fig. 3 is a side elevation of the heating device of Fig. 1 partly broken away;

Fig. 4 is a front elevation similar to Fig. 2 of a somewhat different form of heating device;

Fig. 5 is a vertical section of the control valve of Fig. 2 drawn to an enlarged scale;

Fig. 6 is a perspective detailed view showing the arrangement of the dampers;

Fig. 7 is a sectional front elevation of the heating element taken on the line 7-7 of Fig. 3;

Fig. 8 is a sectional side elevation of the heating element taken on the line 8-8 of Fig. 2;

Fig. 9 is a diagrammatic sketch indicating the approximate course taken by the air currents; and

Fig. 10 is a diagrammatic sketch indicating the approximate course taken by the air currents with a somewhat different type of heater.

The reference character 21 indicates a circulation box or compartment in which is positioned a heater 22 of some suitable type. As shown in Figs. 2, 7 and 8, this heater comprises a chamber 23 for steam, hot water, or other heating medium which chamber has a plurality of outwardly extending fins 24 lying in vertical planes and preferably parallel with the smaller dimension of the chamber 23, i. e., extending from the front to the back of the compartment 21. The front and rear walls of the chamber 23 may be connected with reinforcing braces 23a. It is very desirable, in many instances, that the heating device be out of the way as much as possible, and for this purpose the width may be sufficiently narrow so that it can be placed between adjacent studs 25 and 26 of the wall of a room as shown in Fig. 1, and the height may be sufficiently low so that it may be placed between the floor 27 and the first cross bridging 28. If installed in a wall the thickness of the heater should not be greater than the thickness of the walls, a common dimension being four inches as the studs 25 and 26 are usually 2 x 4. At the upper portion of the box 21 there may be provided a discharge orifice 29, which is shown as sub-

90
95
100

divided into a plurality of openings. At the lower portion of the circulation box 21 there may be provided an inlet orifice 30 which is on the room side of the heating device, and there may also be provided an inlet orifice 31 which connects with a source of fresh air such as the outside atmosphere if the heater is installed in the outside wall of a room.

A suitable blower 32 is positioned in the circulation box 21 under the heater 22 and between the two inlet orifices 30 and 31. The blower may be of a centrifugal type having radially extending vanes 33 which drive the air upwardly and outwardly through a passage 34. The air passes over the surface of the chamber 23 and the fins 24 and out through the discharge orifice 29, the shape of the circulation box directing the discharged air in a substantially horizontal direction. The blower may draw the air through an inlet duct 35 opposite the inlet orifice 30 opening into the room or it may draw air through an inlet duct 36 opposite the inlet orifice 31 which supplies fresh air. Dampers 37 and 38 may be provided for controlling the amount of air passing into the orifices 30 and 31 respectively. The dampers are preferably controlled together in such a manner that opening one operates to close the other. For this purpose a transverse shaft 39 may be provided suitably journaled in the frame of the blower 32 and in the frame of the circulation box 21, and may have a damper-control knob 40. The dampers 37 and 38 are secured to the shaft 39 at different angular positions so that one will be open when the other is closed and vice versa. As shown in Figs. 2 and 3, the damper 37 controlling the inlet orifice 30 is closed and the damper 38 controlling the inlet orifice 31 is open. By turning the damper-control knob 40 clockwise, the damper 37 is gradually opened, while the damper 38 is being closed. The blower 32 may be driven by an electric motor 41 provided with a driving pulley 42 and driving through a belt 43 a pulley 44 secured to the shaft of the blower 32. Instead of a belt drive the motor may, if desired, be directly connected to the shaft of the blower.

The chamber 23 is provided with an upper and a lower threaded projection 51 and 52 for connection with a supply pipe 53 and an exhaust pipe 54 for the steam or hot water or other fluid for supplying heat to the heater. In order to insure complete circulation of heating fluid throughout the chamber 23 a deflecting shelf 54a may be provided which extends between the inlet projection 51 and the outlet projection 52, across the chamber and downwardly to within a short distance of the opposite wall. An electrically controlled valve 55 may be placed in the supply pipe 53 to control the supply of heating fluid. The valve 55 has an inlet opening at 56 (Fig. 5) and an outlet opening at 57 and a passage

58 therebetween. A valve seat 59 is provided at the passage 58 and is closed by a valve disc 60 carried by a valve rod 61 of iron or other suitable magnetic material. The upper end of the valve 55 may be surrounded by an operating coil or solenoid 62 and rests against a shoulder 63 on the valve body and is held in place by a cap 64. A compression spring 65 is positioned between the valve rod 61 and the cap 64 and tends to hold the valve disc 60 against its seat 59. When energized, the coil or solenoid 62 draws the valve rod 61, which acts as a magnetic plunger, upwardly and opens the valve. In the form of valve just described the solenoid is energized during the whole time that the valve is open and should be so designed as to require very little energy for its excitation. In place of the valve shown other valves may, if desired, be employed which do not require current continuously but only during the period of opening and of closing. While the valve 55 is shown near the heating device it is to be understood that it may be placed, if desired, some distance away as in the basement of the house or elsewhere. Also the projections 51 and 52 may extend downward from the chamber 23 instead of laterally therefrom in which case the electrically controlled valve 55 may be in the lower part of the circulation box 21 with the blower or it may be placed outside of the box and at some distance away.

The electric motor 41 for the blower is supplied with electrical energy by means of conductors 66 and 67. The electric valve 55 receives its energy through conductors 68 and 69 which may, if desired, be connected to the conductors 66 and 67 so as to be simultaneously energized therewith or the conductors 68 and 69 to the valve 55 may be independently controlled. A manually controlled switch is indicated at 70, but it is to be understood that a thermostatically controlled switch may be employed so that the heating device starts and stops automatically in accordance with the temperature of the room being heated. While the steam supply has been shown as being simultaneously controlled with the operation of the blower, it may be possible to omit the electrically controlled steam valve control in certain cases. This is because the amount of heat carried into the room is many times greater when the forced circulation is taking place than when the blower is not running, so that the mere stopping of the blower also stops the heating for most practical purposes.

In the form of heating device shown in Fig. 4 the heating is done by means of electrical energy supplied to an electric heater 22a through conductors 68a and 69a.

In the operation of both forms of heating devices shown in the drawings, the air is drawn into the inlet orifice 30 or 31, is drawn upwardly and over the heater, and is dis-

charged out through the discharge orifice 29. The circulation box is so shaped, as by being curved as indicated at 71, assisted in some cases by an overhanging lip 71a, that the air is discharged in a substantially horizontal direction. This horizontal type of discharge is one of the important features of the invention and should be at a velocity sufficiently great to carry the air well into the room. A heater which depends upon circulation from the natural convection currents, moves the air chiefly or to a large extent in a vertical direction. With the present invention, however, the air is discharged in a substantially horizontal direction at a velocity which is considerably in excess of the velocities due to convection currents. The heated air therefore passes more in a horizontal direction, although the initial horizontal component of the velocity gradually decreases in amount, and the upward tendency from convection currents continues to persist until the heated air has fully mingled with the rest of the air in the room. In this way the upward movement of the heated air becomes relatively greater as the air passes across the room with the result that the movement which is initially almost altogether in a horizontal direction finally becomes almost altogether an upward movement. This is illustrated by the arrows A in Fig. 9. The heater is preferably located in the outside wall of a room and may be under a window 72. The air which is cooled by passing over the cool wall or which leaks through the window passes downward as at C and unites with the stream of air discharging from the heating device.

Another feature of the invention which is important is the principle of using a relatively large quantity of air and raising its temperature only a little as distinguished from heating a relatively small quantity of air to a temperature much above that of the room. The use of a large quantity of air at a temperature which does not differ too greatly from the average temperature of the room which is being heated eliminates the sensation of undue heat being experienced by those in the room. The elimination of sensations of uneven heating or drafts is also promoted by keeping the discharge velocity down to a relatively low value although it should be sufficient to carry the air well into the room in a substantially horizontal direction. The direction of the inlet air is indicated by the arrows B in Fig. 9. It will be observed that, in this figure, the air is drawn principally from close to the floor with a gradually increasing tendency to draw air from the sides instead of from directly in front of the inlet orifice. In order to give an approximate idea of relative proportions, the heater in Fig. 9 is shown as being positioned under a window 72. The level in the room at which air is breathed is of considera-

ble importance in connection with heating and ventilation and this so-called "breathing line" is indicated at 73 in Fig. 9. It has been found, in the course of the present experiments, that it is desirable that both the level of the inlet air as indicated at B and the level of the discharged air as indicated at A should be below the breathing line.

In Fig. 10, the circulation box 21 has inlet orifices 30a and 31a at the upper portion of the box and a discharge orifice 29a at the lower portion of the box. With such an arrangement the air is drawn in as indicated by the arrows B and discharged in a substantially horizontal direction along the floor 27 as indicated by the arrows A, a curved portion 71a of the circulation box directing the air as desired.

In the foregoing description, the heating device has been described as being installed in the wall of a room, but it is not necessarily confined to such a type of installation. The heater may be of a portable type, particularly when built as an electrical heater. It may be installed in the space provided for an open fire place, under a bookcase, or in some instances, away from the wall of a room. It is very effective in distributing the heat across the lower portion of a room which is just the place where heat is required, and by keeping the circulating air below the breathing line and by raising its temperature only moderately there are no noticeable currents of air produced even a short distance away from the heating device. Furthermore, by producing a positive flow of air over the surface of the heater it is possible to make it much smaller and lighter and more compact, a heater constructed in accordance with the present invention frequently being found capable of doing as much heating as a standard radiator of many times its weight.

Another advantage of the invention which should be mentioned is that the outward horizontal direction of the discharged air has but little tendency to discolor the walls, draperies, etc., above the heater, a tendency which is very marked in many other types of heaters and which frequently governs the choice of location of the heater which might otherwise be more effectively situated for its primary function, that of heating. The individual control of the heating of each room which is an inherent part of the invention makes it possible to control the heat so as to give perfect heating for each and every room regardless of any variation in heating requirements for different rooms. Also, as the amount of heating is chiefly dependent on the operation of the blower which can be started and stopped promptly, the heating is under almost perfect control.

It is to be understood that the hereinbefore described embodiments of the invention are for the purpose of illustration only

and various changes may be made therein without departing from the spirit and scope of the invention as defined in the subjoined claims.

I claim:

1. A heat exchange device adapted for installation within the wall of an ordinary room comprising a circulation box, a discharge orifice for discharging heated air into the room to be heated, an inlet orifice for drawing air from the room being heated, one of said orifices being positioned in the upper, and the other in the lower region of the box, a second inlet orifice in the region of the aforesaid orifice and connected with a source of fresh air, dampers for said inlet orifices, means for simultaneously operating said dampers whereby one is being opened while the other is being closed, said dampers being mounted on a common horizontal shaft and adapted to move in a vertically arcuate direction, a heat exchanger positioned within said box between the discharge orifice and the inlet orifices, and means positioned within said box for producing a forced circulation of air from the inlet orifices, over the surface of the heat exchanger and out of the discharge orifice.
2. A heat exchange device comprising a circulation box, a discharge orifice for discharging heated air into the room to be heated, an inlet orifice one of said orifices being positioned in the upper, and the other in the lower region of the box, a circulating fluid heat exchanger positioned within the box between said orifices, an air circulating device positioned within said box for producing a forced circulation of air into the inlet orifice, over the surface of the heat exchanger and out of the discharge orifice, an electric motor for driving said air circulating device, electrically operated control means for supplying fluid to said heat exchanger, and means for starting the operation of said motor and said control means simultaneously.

3. A heat exchange device adapted for installation within the wall of an ordinary room comprising a circulation box of less width than the space between the adjacent wall studs, a discharge orifice for discharging heated air into the room to be heated, an inlet orifice one of said orifices being positioned in the upper, and the other in the lower region of the box, a fluid chamber positioned between said orifices and having an inlet pipe and an outlet pipe, a plurality of fins extending from said chamber substantially vertically and at right angles to the plane of the wall, an electrically controlled valve in said inlet pipe, a motor driven air circulating device for drawing air into the inlet orifice, over the surface of the chamber and fins and out of the discharge orifice, and means for simultaneously supplying said motor and said valve with electrical energy for operation.

4. A heat exchange device adapted for installation within the wall of an ordinary room comprising a circulation box of less width than the space between the adjacent wall studs, a discharge orifice positioned at the upper portion of said box for discharging heated air into the room to be heated, an indoor air inlet and an outdoor air inlet positioned in the lower portion of said box with dampers for said inlet orifices, and means for simultaneously operating said dampers whereby one is opened while the other is being closed, a fluid chamber positioned between said orifices, and having an inlet pipe and an outlet pipe, a plurality of fins extending from said chamber substantially vertically and at right angles to the plane of the wall, an electrically controlled valve in said inlet pipe, a motor driven air circulating device for drawing air into the inlet orifices, over the surface of the chamber and fins and out of the discharge orifice, and means for simultaneously supplying said motor and said valve with electrical energy for operation.

5. A heat transfer device comprising a circulation box, a discharge orifice for discharging air into a room, an inlet orifice one of said orifices being positioned in the upper, and the other in the lower region of the box, a circulating fluid heat exchanger positioned within the box between said orifices, means positioned within said box for producing a forced circulation of air into the inlet orifice over the surface of the heat exchanger and out of the discharge orifice, an electrically operated valve for controlling the supply of fluid to said heat exchanger, and means for simultaneously starting the operation of the circulating means and opening said valve.

Signed by me this 14th day of October, 1929.

WALTER L. MACK.
